UNITED STATES PATENT OFFICE

2,478,950

GUN COOLING SYSTEM

Nelson E. Spurling, United States Navy

Application August 2, 1945, Serial No. 608,559

3. Claims. (Cl. 89—14.1)

(Granted under the act of March 3, 1883, as amended April 30, 1928; 370 O. G. 757)

1

The present invention relates to a device for air cooling firearms.

It is an object of the present invention to provide means for cooling firearms.

Another object of the present invention is the provision of an air cooling means for gun installations on vehicles as, for example, in the wings and fuselage of fighter and dive bomber aircraft.

A still further object of the present invention is the utilization of the ram effect of air caused by the high forward velocity of airplanes when in flight.

A still further object of the present invention is the provision of means for causing air to circulate in a swirling movement around the barrel of firearms.

Other objects and advantages will become apparent as the description proceeds, and is taken in connection with the accompanying drawings wherein like characters of reference designate corresponding parts throughout the several views, and wherein:

Fig. 1 is a side elevational view of a gun and illustrating an air inlet and an air outlet;

Fig. 2 is a front elevational view of Fig. 1;

Fig. 3 is a sectional view taken on line 3—3 of Fig. 1, looking in the direction of the arrows;

Fig. 4 is a modified form of the invention and illustrating a fragmentary section of a wing, portions being broken and in section and illustrating a gun mounted therein; and

Fig. 5 is a partial longitudinal sectional view taken on line 5—5 of Fig. 2, portions being broken.

Referring to the drawings, the numeral 10 represents a plate having apertures 11 that receive bolts for securing the plate to a suitable support. The plate is provided with a scoop portion 12 that may be integral with the plate, and an opening 13. The scoop may be so located as to feed cooling air into a gun cooling tube. The opening 13 receives a tube 14, and superimposed upon the tube 14 is an air intake tube 15, the upper portion 16 of which is of substantially circular configuration, and as shown in Figs. 2 and 3, forms an eccentric sleeve. The tubes 14 and 15 are held together by a connecting tube 17. The portion 16 encompasses a sleeve 18 that is provided with a plurality of apertures 19, as shown in Figs. 3 and 5. The sleeve 18 at one end receives a barrel jacket 20, a portion of the outer wall of which snugly engages the inner wall of the sleeve 18, as shown in Fig. 5. The opposite end wall 21 of the jacket 20 is provided with an aperture 22, the wall of the jacket being pro-

vided with apertures 23. The sleeve 18 and the jacket 20 comprise an encasement which encompasses a gun barrel 24, one end 25 protruding through the aperture 22. The inner walls of the sleeve 18 and jacket 20 are in spaced relation to the gun barrel 24, thus forming a channel 26. The rear portion 27 of the sleeve 18 is connected to a gun receiver 28 and it is secured thereto by an adjustable clamping ring 29. As indicated by the arrows, air enters the mouth of the scoop 12, passes through the tubes 14 and 15 to the circular portion 16, and being in a turbulent state, enters the apertures 19 and with a swirling motion around the gun barrel 24, exudes out of apertures 23.

In the modified structure illustrated in Fig. 4, the numeral 30 represents a fragmentary wing portion partly in section. Within the wing 30 is mounted a gun having a barrel 31, a receiver 32, a barrel jacket 33 that is provided with a plurality of apertures 35 and a securing element 34. Encompassing the jacket 33 is a tubular element 36 that provides a cooling compartment, the inner wall of which is in spaced relation to the jacket 33. The wing 30 is provided at the leading edge with a blast tube opening 37 that communicates with the cooling compartment, and a spacer tube 38 for closing the compartment 36. The underside of the wing is provided with an opening 39 that is provided with a well known louvre type air scoop and for this reason, the same is not shown. The opening is in communication with the tubular element 36. The top portion of the wing is provided with an air exit 40 and it is in communication with the tubular element 36. If desired, a Pitot tube 41 may be placed in the exit or outlet opening 40.

In the use of the device as illustrated in Fig. 1, air is forced into the scoop 12 due to the high forward velocity of an airplane, the air passing through the tubes 14 and 15 into the head 16, as shown by the arrows, Fig. 3, where it is given increased force and passing through the openings 19 is given a swirling motion around the gun barrel 24. As the air heats up from contact with the hot gun barrel, it is forced along the barrel by the cooler air until it is discharged through apertures 23. In the form of the invention illustrated in Fig. 4, the air stream enters the opening 39 and circulates around the barrel jacket 33 infiltrating through the apertures 35 around the gun barrel 24, escaping through the opening 40 as indicated by the arrows. It will be understood that the above description and accompanying drawings comprehend only the general embodi-

ment of my invention and that various changes in construction, proportion and arrangement of parts may be made within the scope of the appended claims without sacrificing any of the advantages of my invention.

The invention described herein may be manufactured and used by or for the Government of the United States of America for governmental purposes without the payment of any royalties thereon or therefor.

What I claim is:

1. In a vehicle, a gun, including a barrel, mounted on the vehicle, cooling means for the gun comprising a substantially circular encasement for the barrel of the gun, said encasement being spaced from the gun barrel to define a channel and having channel closures adjacent the muzzle and breech ends thereof, said encasement having apertures adjacent the respective channel closures, an air intake tube extending off from the breech end of the encasement, an air scoop at the outer end of the tube, and a casing portion at the inner end of the tube, said casing portion being emplaced on the breech end of the encasement in confining relationship to the adjacent apertures and eccentrically of said encasement.

2. In a vehicle, a gun, including a barrel, mounted on the vehicle, cooling means for the gun comprising an encasement for the barrel of the gun, said encasement being spaced from the gun barrel to define a channel and having channel closures adjacent the muzzle and breech ends thereof, said encasement having apertures adjacent the respective channel closures, an air intake tube having an air scoop at one of its ends, and a circular casing portion coupling the other end of the intake tube with the encasement, and having the intake tube extending tangentially therefrom, said casing portion being mounted on the encasement over the apertures adjacent to the gun breech and eccentrically of the encasement to initiate a swirling motion of the air stream around the gun barrel prior to

driving it forwardly in the channel and along the barrel for escape at the apertures adjacent to the gun muzzle closure.

3. In a vehicle, a gun, including a barrel, mounted on the vehicle, cooling means for the gun comprising a substantially circular encasement for the barrel, said encasement having closures at its ends bearing on the gun barrel and defining the terminals of a channel around the barrel, the encasement also having apertures adjoining each end closure, and air inductor means depending from said encasement over the apertures adjoining the breech end of the encasement and mounted eccentrically thereto, said inductor means projecting into the confronting air stream to divert a portion thereof for a reverse flow through the channel and out of the apertures adjoining the muzzle end of said gun.
